United States Patent Office.

THOMAS M. RASER AND THOMAS J. RASER, OF PHILADELPHIA, PENNSYLVANIA.

Letters Patent No. 67,137, dated July 23, 1867.

IMPROVED BOAT-DETACHING TACKLE.

The Schedule referred to in these Letters Patent and making part of the same.

TO ALL WHOM IT MAY CONCERN:

Be it known that we, THOMAS M. RASER and THOMAS J. RASER, both of Philadelphia, in the county of Philadelphia, and State of Pennsylvania, have invented a new and useful Improvement in Self-Detaching Davit-Hooks for lowering boats from vessels; and we do hereby declare that the following is a full, clear, and exact description thereof, reference being had to the accompanying drawings, and to the letters of reference marked thereon.

The object of our invention is to provide a hook for lowering boats which will automatically detach itself as soon as the boat reaches the water, and thus obviate the danger of the boat's swamping by reason of not being released at the proper time. In the accompanying drawings—

Figure 1 represents a side elevation of our hook when closed, and sustaining the weight of the boat suspended thereto; and

Figure 2 represents the same when open, after it has been detached from the boat.

A and A' are the two jaws of the hooks, pivoted together at *a*. These jaws are jointed together by means of a tenon, *t*, on A', entering an open mortise or slot in A. B is a shackle attached by same pivot *a*, on which the two jaws of the hook turn. *b* is a spring to open the hook and keep it open when no weight is attached, and the pin *f* not inserted to keep it closed. This spring passes through the mortise or slot in A, the lower end of which slot is indicated by a dotted line, *s*. *c* is a latch-spring, with catch *c'* to hold the ends of jaws A A' together when the boat is suspended by the hooks. *d* is a tongue on the end of one of the jaws, which fits into a corresponding groove, *d'*, in the end of the opposite jaw. *e* is a catch on the tongue *d*, which engages with the catch on the end of the latch-spring when the hook is closed, and a sufficient weight bearing on said latch-spring to press it down. *f* is a pin suspended to the shackle by a chain, which may be inserted through both jaws of the hook, as shown in fig. 1, to keep the hook closed when not in use in lowering the boat. *i* is a check-pin, firmly fixed in one of the jaws of the hook, and projecting into a curved groove, *j*, in the other jaw, the said groove being so made as to limit the spread of the hook. *g* is a guard-plate on each side of the tongue *d*, and rising up flush with the catch *e*, to prevent the ring or link into which the hook engages from being caught or detained by said catch *e* when the hook opens.

It will be seen that when the hook is closed, as shown in fig. 1, and the boat suspended by it, the ring or link with which the hook engages will press down the latch-spring *c*, and cause its catch *c'* to engage with the catch *e* on the tongue of the opposite jaw, thus holding the two jaws of the hook firmly together. But as soon as the boat rests upon the water, the pressure upon the latch-spring *c* will be relieved, and the spring will rise, disengaging the catch *e*, when the spring *b* will immediately throw the jaws of the hook asunder and release the boat.

Having thus described our invention, what we claim as new, and desire to secure by Letters Patent, is—

1. In combination with the two jaws of the hook, pivoted together as described, the spring *b*, latch-spring *c*, with its catch *c'*, tongue *d*, with its catch *e*, and the groove *d'*, all constructed and operating substantially as described.

2. In combination with a hook constructed and operating as above described, I claim the pin *f*, as and for the purpose described.

3. In combination with a hook constructed and operating as described, I claim the check-pin *i* and groove *j*, as and for the purpose described.

4. In combination with the tongue *d* and groove *d'*, I claim the guard-plates *g* on each side of the tongue, arranged and operating as and for the purpose described.

THOMAS M. RASER,
THOMAS J. RASER.
